UNITED STATES PATENT OFFICE.

HUGH J. KNOWLTON AND FRED H. CHEEVER, OF NEW HAVEN,
CONNECTICUT.

DESIGN FOR A TOOTH-BRUSH HOLDER.

SPECIFICATION forming part of Design No. 35,411, dated December 10, 1901.

Application filed October 26, 1901. Serial No. 80,146. Term of patent 7 years.

To all whom it may concern:

Be it known that we, HUGH J. KNOWLTON and FRED H. CHEEVER, citizens of the United States, residing in the city of New Haven, county of New Haven, State of Connecticut, have invented and produced a new and original Design for Tooth-Brush Holders, of which the following is a specification, reference being had to the accompanying drawing, forming a part thereof, and in which the single figure is an elevation in perspective, showing a tooth-brush holder embodying our design.

As shown by the drawing, the design embodies as its essential features a base A, the upper surface of which is concave, as indicated by A', said base being surmounted by a series of vertical rods B, the lower ends of which are secured in posts affixed to said base, as indicated at a, having at their upper ends arms B', to which are secured clasps C, the whole forming an ornamental base and holder for tooth-brushes or similar articles.

Other minor features of the design are the configuration of the outer vertical rods, which, as will be seen in the drawing, flare out in a 25 graceful manner, and the twisting of the upper end of said central vertical rod to form an eye.

Having described our invention, what we claim, and desire to secure by Letters Patent, 30 is—

The design for a tooth-brush holder, as herein shown and described.

In witness whereof we have hereunto set our hands, at New Haven, in the county of 35 New Haven, this 24th day of October, 1901.

HUGH J. KNOWLTON.
FRED H. CHEEVER.
